SKINS**

(76) Inventor: **Stephen Payn**

Stephen Faqul,
Letter Patent
Signed March 31, 1806.

The machine referred to in these letters patent & making part of the same, containing a description in the words of the said Stephen Faqul himself of his machine for splitting skins or Neats leather.

This machine consists of three principal parts, viz. Of a Frame of a triangular form firmly fixed to the floor of the Room, this Frame supports a roller, at one end of which is attached a saw or spur wheel, which is moved or operated upon by means of a lever or handle at the back of the machine: The one end of this machine is suspended a Titch, which catches in the teeth of the wheel, turning it and drawing the leather attached to the roller right & downward.

Above the roller is a Beam or plate with an opening corresponding to the segment of the circle formed by the spur: Through this opening the skin is drawn downward, by the lever, with the hand, as the spur cuts it with the other hand of the operator.

2nd The Press, which has a curve corresponding to the opening in the Plate is brought down to cover and buttons on the skin to keep it end while cutting.

3rd The Sump is a heavy Beam, but taking considerably at one end which is fixed in a frame in an upright post to which it turns: This end has several holes in any of which the sun may be admitted & thus regulated.

according to the thickness of the leather, at the other end of the beam is fixed a dome, curving in the form of a keyboard piano which splits the leather.

Stephen Fugit,
Holder of Patent
Second March 31, 1806.

The invention relates to the skinning & preparing part of the same, containing a description in the words of the said Stephen Fugit, inventor of the machine for splitting skins or leather.

This machine consists of three principal parts viz. 1st. Of a Frame, of a triangular form firmly fixed to the floor of the room. This Frame supports a roller, at one end of which is attached a bar or skin roller, which is moved or operated upon by means of a lever or handle at the back of the machine. To the one end of this machine is annexed a tooth, which catches in the teeth of the wheel turning it and drawing the leather attached to the roller right & leftward.

Above the roller is a beam or plate with an opening corresponding to the segment of the circle formed by the roller. Through this opening the skin is drawn downward, by the lever, with the hand, as the scurf cuts it with the other hand of the operator.

2nd. The scurf, which has a cut corresponding to the opening in the Plate is brought down a scurf and buttons on the skin to keep it smooth while cutting.

3rd. The scurf is a heavy beam, but tapering considerably at one end which is fixed on a pin in an upright post on which it turns. This end has several holes, in any of which the pin may be admitted & thus raised & lowered.

United States Patent

Patent No.: X680

according to the thickness of the leather, at the other end of the beam is fixed a 46 mils quantity in the form of a rectangular frame which holds the leather.
